SANDING APPARATUS

Guilford S. Turner, Chicago, Ill., assignor to Morris B. Brewster Co. Inc., Chicago, Ill., a corporation of Illinois

Application May 24, 1937, Serial No. 144,392

5 Claims. (Cl. 291—11)

The invention relates to sanding apparatus.

One object of the invention is to provide an improved remote control valve whereby a cleaning blast of air will be delivered to the sand delivery pipe when the sander-trap is operated.

Another object of the invention is to provide an improved remote control valve whereby a cleaning blast of air will be delivered to the sand delivery pipe when the sander is initially operated and which will deliver a small volume of air to the clean-out duct continuously during the operation of the sander to prevent particles of sand from working back into the piping between the trap and control valve.

Another object of the invention is to provide an improved remote control valve for sanding apparatus, which is simple in construction, efficient in operation, and can be produced at a low cost.

Other objects of the invention will appear from a consideration of the following detailed description.

The invention consists in the several novel features which are hereinafter set forth and are more particularly defined by claims at the conclusion hereof.

In the drawing:

Fig. 1 is a sectional view of sanding apparatus embodying the invention.

Fig. 2 is a section of the remote control valve in its operative position which it assumes while the sand-trap is operative to discharge sand to the sand delivery pipes.

Fig. 3 is a section of a modified form of the invention.

The invention is exemplified in connection with a sander-trap 10 which comprises a nozzle 11 for delivering air under pressure to force the sand entering the trap from a delivery pipe 12 through the trap-body and through the pipe 13 for delivering the sand to one of the wheels or rails. A duct 14 is provided in the outlet portion of the sander casing for directing a cleaning blast into the upper end of the pipe 13 for blowing out the pipe at the beginning and also at the end of each track-sanding operation.

The remote control valve comprises a generally cylindrical casing 15 in the upper end of which is formed a cylinder 17 in which a piston 18 is slidable. A head 16 is removably secured to and closes the top of the casing 15. A pipe 19 from the usual operator's control-valve (not shown) is connected to the head 16 to deliver air under pressure into cylinder 17 for shifting the piston 18. A spring 20 normally holds the piston

raised and serves to retract it when the pressure on piston 18 is released. A pipe 21 connects the head 16 and the nozzle 11 to deliver air under pressure from cylinder 17 to the nozzle 11 in the trap. The pipe 19 is usually of slightly greater capacity than the pipe 21 or the nozzle 11 to cause sufficient pressure to be built up in the cylinder 17 and force the piston 18 downwardly while the sander is in operation.

The piston 18 comprises a packing-ring 18^b which is secured by a follower 18^c and nut 18^a against the top of the body of piston 18. Said piston body is secured by the nut against a shoulder 22^a on a combined stem 22 for the piston 18 and a valve 25. The piston 18 shifts stem 22 to operate the valve 25 for controlling the clean-out blasts. The piston, cylinder and spring 20 serve as fluid-pressure and spring-controlled means for shifting the valve.

When the sander is idle, valve 25 will be held 20 against a seat 15^a to cut off air from the supply reservoir to the blow-out duct 14.

The lower end of casing 15 is provided with a cylindrical chamber 15^a and a smaller chamber 24 above and in communication with said chamber 15^a, and has a cap 31 which is screw-threaded into and shouldered against the casing to form a fluid-tight connection. A pipe 35 threaded into cap 31, is connected to the usual air reservoir and serves to deliver air under pressure to the casing 15 for delivery to the cleanout duct. A pipe 32 is threaded into one side of the casing 15 and into the sander-trap 10 to deliver fluid under pressure from the casing 15 to the cleanout duct. Usually two openings 33 are provided 35 in casing 15 for convenience in attaching the pipe 32 to the casing. The opening 33 which is not used, is closed by a plug 34. The casing 15 is provided with ears or lugs 15^d whereby it may be mounted in any desired position on the locomotive.

The opening in the casing leading to pipe 32 communicates with the cylindrical chamber 24. At the lower end of chamber 24 the valve-seat 15^a is formed. An annular inclined upwardly 45 facing valve-seat 30 is formed in the top of the cap 31. The valve-stem 22 carries at its lower end the valve 25 which has an upwardly convergent annular face 26 for engaging the seat 15^a and a downwardly convergent annular face 50 28 adapted to fit on and engage the seat 30 in the cap 31. Valve 25 operates vertically in and across a chamber 15^b in the casing 15 between valve-seats 15^a and 30. When the sander-trap 55 is not in operation, the spring 20 will hold the

piston 18, valve-stem 22 and valve 25 raised in the position shown in Fig. 1. At this time annular face 26 of valve 25 will be against seat 15^a and no air from the supply pipe 35 will pass from chamber 15^b to the clean-out pipe 32.

When the piston 18 is shifted at the beginning of a sanding operation, it will lower valve 25 away from seat 15^a and permit a blast of air from pipe 35 to pass through valve-seat 30, chambers 15^b and 24, pipe 32, to the clean-out duct 14. When the valve 25 is arrested by valve-seat 30, the valve will cut off the air from pipe 35 and discontinue the cleaning blast. At the end of a sanding operation, when the pressure in cylinder 17 is released and with the aid of pressure from pipe 35, valve 25 will be restored to its normal position in engagement with valve-seat 15^a and, after permitting a cleaning blast to pass to the duct 14, will cut off the air to the cleaning duct 14 while the sander is idle.

A small angular port 36 is formed in valve 25 to permit air to leak or slowly flow from pipe 35 through valve 25 and into chambers 15^b, 24 to pipe 32 and to the clean-out port 14 while the face 28 of valve 25 engages seat 30 on cap 31, which position it assumes during the operation of the sander. This port delivers a small stream of air to blow-out duct 14 to prevent effectively any sand from being drawn or blown into the line leading to the remote control valve.

In the modification illustrated in Fig. 3 a small groove 37 is formed in the valve-seat 30 to permit air to leak past valve 25 to the pipe 32, while the sander is in operation, and said valve is seated on seat 30.

In operation, the engineer will, through the usual operating valve located in the engineer's cab of the locomotive, admit air under pressure through pipe 19 into the cylinder 17 from which it will pass through pipe 21 to the nozzle 11. Normally the valve 25 is held against seat 15^a by spring 20. The pressure in the cylinder 17 of the remote control valve will shift the piston 18 to move valve 25 away from valve-seat 15^a and against valve-seat 30. During the downward movement of the valve 25, air under pressure from pipe 35 will flow around valve 25 through chambers 15^b, 24 and thence through pipe 32 and blow-out duct 14 into the sander-pipe 13. When the valve-face 28 engages valve-seat 30 the main supply of air from the reservoir through pipe 35 to the blow-out duct, will be cut off.

During the operation of the sander, valve 25 remains against the seat 30 in cap 31 and air under pressure will leak or flow slowly through duct 36 in valve 25 or groove 37 in valve-seat 30 to cause a small flow of air through pipe 32 and the duct 14 so that during the operation of the nozzle 11, the entry of sand into the pipe 32 and the remote control valve will be prevented.

The leak-port remains effective while the sander is in operation and the blast to the clean-out duct is cut off at the remote control valve for the purpose of preventing the entry of sand into the line between the trap and the valve-casing and into the valve-casing where sand may interfere with the seating of the valve.

The single double acting valve with opposite faces for cutting off the supply of fluid before and after the clean-out blast, provides a simple and inexpensive construction. By forming one of the valve-seats in the cap at the lower end of the casing, the removability of the cap makes it easy to re-shape the seat if necessary.

75 The valve with oppositely facing valve-faces

and co-acting with tapered seats, respectively, has been found to be efficient in use and leakage which frequently occurs when cylindrical valves are used, has been avoided.

The invention is not to be understood as restricted to the details set forth, since these may be modified within the scope of the appended claims, without departing from the spirit and scope of the invention.

Having thus described the invention, what I claim as new and desire to secure by Letters Patent is:

1. The combination with a sand-trap provided with a nozzle for a sanding blast and a duct for a cleaning blast, of a valve-casing, connections 15 for delivering fluid under pressure to the casing and from the casing to the clean-out duct, valve-means slidably mounted in the casing, adapted to cut off the fluid to the clean-out duct from the casing and to control a cleaning blast of limited duration, to the clean-out duct and from the casing, valve-shifting means, and means for flowing a small quantity of fluid from the casing to the clean-out duct after the valve-means has been operated to cut off the clean-out blast and 25 during the operation of the trap.

2. The combination with a sand-trap provided with a nozzle for a sanding blast and a duct for a cleaning blast, of a valve-casing, connections 30 for delivering fluid under pressure to the casing and from the casing to the clean-out duct, a valve-member slidably mounted in the casing, adapted to cut off the fluid to the clean-out duct from the casing and to control a cleaning blast of limited duration, to the clean-out duct and 35 from the casing, valve-shifting means, and means in the form of a leak port in the valve-member for flowing a small quantity of fluid from the casing to the clean-out duct after the valve-member has been operated to cut off the 40 clean-out blast and during the operation of the trap.

3. The combination with a sand-trap provided with a nozzle for a sanding blast and a duct for a cleaning blast, of a valve-casing, connections 45 for delivering fluid under pressure to the casing and from the casing to the clean-out duct, valve-means slidably mounted in the casing, adapted to cut off the fluid to the clean-out duct from the casing, and to control the valve-means 50 for delivering a cleaning blast of limited duration, to the clean-out duct and from the casing, valve shifting means, and means in the form of a small groove in the casing for flowing a small quantity of fluid from the casing to the clean-out 55 duct after the valve-means has been operated to cut off the clean-out blast and during the operation of the trap.

4. The combination with a sand-trap provided with a jet for a sanding blast and a duct for a 60 cleaning-blast, of a valve-casing comprising a body and a removable cap at one end of the body, a pipe for delivering fluid under pressure to the casing, leading into and connected to the cap, a connection for delivering fluid from the casing 65 to the clean-out duct, a valve-member for cutting off the fluid from the casing to the clean-out duct, slidably mounted in the casing and having oppositely disposed faces, correspondingly disposed valve seats, one of which is formed 70 in the cap and the other of which is formed in the body of the casing, adapted to be engaged, respectively, by the faces of the valve-member to cut off the fluid to the clean-out duct, and to control, when it passes between the seats, a 75

clean-out blast of limited duration, and means for shifting said valve.

5. The combination with a sand-trap provided with a jet for a sanding blast and a duct for a cleaning-blast, of a valve-casing comprising a body and a removable cap at one end of the body, a pipe for delivering fluid under pressure to the casing, leading into and connected to the cap, a connection for delivering fluid from the 10 casing to the clean-out duct, a valve-member for cutting off the fluid from the casing to the clean-out duct, slidably mounted in the casing

and having oppositely disposed inclined faces, correspondingly inclined valve-seats, one of which is formed in the cap and the other of which is formed in the body of the casing, adapted to be engaged, respectively, by the faces 5 of the valve-member to cut off the fluid to the clean-out duct and to control, when it passes between the seats, a clean-out blast of limited duration, a stem on the valve, a cylinder in the casing, and a piston in the cylinder and connect- 10 ed to the stem.
